FLUTING MACHINE

Application filed January 6, 1927. Serial No. 159,295.

The invention relates to fluting machines and its general object is to provide an improved machine of that nature having novel means thereon for the support of a material receiving needle.

In prior constructions, it has been found difficult to prevent the receiving needle from bending or buckling during the operation of the machine. Inasmuch as these needles are of considerable length, it has been found quite difficult to prevent such buckling without impairing the operation of the machine. Thus, a more specific object is to produce a machine of this character in which the receiving needle is supported primarily throughout substantially its entire length, said primary supporting means being retractable as the process of fluting goes on, with a secondary supporting means co-acting to provide the desired support during retraction of said primary means.

In pursuance of the foregoing objects, I aim to provide a fluting machine comprising a pair of intermeshing toothed rolls and material receiving needles positioned with their points arranged to penetrate the material as it is fluted, with means to support the needles up to a point adjacent the rolls, a portion of said supporting means being retractable as increasing amounts of material are threaded upon the needle, and another portion of said means being arranged to support the portion of the needles thus uncovered and having fluted material thereon.

Further objects and advantages will become apparent from the following description of the preferred form of the invention, as shown in the drawings, in which:

Figures 1 and 2 are a plan view and a side elevation, respectively, of the preferred embodiment of the invention.

Fig. 3 is an enlarged vertical section taken through the axes of the fluting rolls.

Fig. 4 is an enlarged vertical section through one of the needle supports.

Fig. 5 is an enlarged section taken on the line 5—5 of Fig. 1.

Fig. 6 is a section on the line 6—6 of Fig. 1, showing the primary and secondary needle supports.

While I have herein disclosed a preferred embodiment of my invention, it is obvious that it is susceptible of various modifications and alternative constructions and it is not my intention to limit the invention to this exact disclosure but to cover in the appended claims all of the various modifications and constructions falling within the scope of the invention.

In the exemplary form disclosed, a base 10 has near one end, a standard 11 secured thereto, which carries a fixed bearing 12 and a vertically slideable bearing 13. A pair of shafts 14 and 15 carrying toothed rolls 16 and 17 are mounted in the bearings 12 and 13 in parallel relation to each other, with the teeth on one roll intermeshing with the teeth on the other. The invention contemplates a series of circumferentially aligned slots or notches 18 through the teeth of each roll, which register to provide apertures 19 (Fig. 3) therebetween in which the points of needles 20 are positioned so as to penetrate the material as the flutes are formed.

Suitable means 21 for raising and lowering the roll 17 mounted on the shaft 15 in the slideable bearings 13, which in this case is shown as being the upper roll, is provided to permit of adjustment of the rolls. The rolls may be driven by a ratchet device 22 on the shaft 14 operated by a suitable hand lever 23, the roll 17 being rotated through its meshing engagement with the driven roll.

A suitable table 24 and guide 25 for directing the material between the rolls may be mounted on one side of the standard 11.

In attaining the major objects of this invention, I prefer to employ an arrangement wherein each needle is supported throughout substantially its entire length, first by a retractable means and then by a second and independent means adapted to guide and progressively to supplant said first mentioned means, as the material is fed upon the needle. In a general way, the attainment of this feature is achieved by the employment of tubular members arranged to surround the needles and in turn to be supported by a jaw-like arrangement of plates which permits a sliding movement of the members therebetween. As the tubes move axially and between the plates,

means are provided thereon which supplant the tubular members in their support of the needles.

While I will, for the purpose of a more concise disclosure, deal with the machine as embodying only one flute receiving needle and the supports therefor, it will be seen from the drawings that the mounting of a plurality of needles is contemplated. Each needle is mounted in the manner to be described and may be used either in conjunction with another or alone as the occasion demands.

In the preferred embodiment shown in the drawings a stationary bed plate 26 is suitably mounted on the base 10, as by the bolts 27, and projects outwardly therefrom in direct alinement with the rolls and table 24. The bed plate 26 carries spaced vertical supports 28, 29 and 30, also in alinement with the rolls, for the mounting thereon of the needles and needle supporting members.

The primary or initial needle support comprises a stationary elongated member, such as the rod 31, adapted to abut the needle 20 and a tubular member 32 mounted on said rod for telescopic movement relative thereto and arranged to surround and support said needle when extended from said rod. The rod 31 is mounted in the support 28 most remote from the rolls and extends towards said rolls parallel to the bed plate 26 and base 10 at a height substantially the same as that of the apertures 19 between the rolls. Slidably mounted on the free end of the rod 31 is the tubular member 32 which passes through suitable openings 33 and 34 in the forward supports 29 and 30. Suitable means such as the collar 35 on the end of the tube 32, is adapted to engage the support 29 to limit the movement of the tube 32 from the rod 31. Preferably an auxiliary tube guide is provided upon the forward support 30 comprising a plate 36 suitably secured on the support and having an upwardly opening U-shaped slot 37 therein arranged to receive the tube 32. The tube is of such diameter as to telescope snugly upon the rod 31 and is substantially larger than the material receiving needle 20 held therein. The tube and the rod are substantially equal in length permitting the ready insertion and removal of the needle when the tube is completely telescoped upon the rod. In this position the guide 36 serves as a temporary rear end support for the needle. As shown, the relative disposition of the members and the posts is such that the needle 20 when held in the tube 32 will abut the rod 31 at one end with the pointed end of the needle projecting beyond the end of the tube and resting in the aperture 19, between the rolls. As the material is fed through the rolls, fluted and threaded upon the needle 20, it will be seen that the needle will be held against bending or buckling by

the tube 32, which, as the material is forced rearwardly on the needle, will be telescoped rearwardly over the rod 31.

However, as the tube slides rearwardly, the needle is not left unsupported. A secondary reenforcing means is provided which, in this instance, holds the needle through the provision of means adapted to engage the material already threaded upon the needle. To this end a pair of plates 38 and 39 are pivotally mounted at one end upon the support 30 on opposite sides of the opening 34 through which the tube 32 passes. Thus the plates 38 and 39 provide a hinged jaw-like device which when closed extends forwardly along the tube, and when opened, as shown in dotted lines Fig. 2, exposes the tubes. On each side of the support 30 and between these plates, a horizontal rib 40 is provided to space the plates a correct distance apart as determined by the diameter of the tube. Means for clamping the plates closed is provided at the free ends thereof comprising herein a pivoted clamp 41, on one plate having an arcuate cam slot 42 therein arranged to engage a pin 43 or the like projecting from the other plate. A suitable handle 44 may be provided to facilitate manual manipulation of the clamp. By this arrangement the tube 32 will be held between the plates 38 and 39 throughout the major portion of its length with the plates sufficiently spaced apart by the ribs 40 to permit the desired sliding movement of the tube therebetween. Any preferred means, such as the stop 45 mounted upon the support 30 is provided as a rest for one plate when they are parted, a suitably resilient pad 46 being positioned on the base as a stop for the other plate.

At spaced intervals on one plate pairs of pointed pins 46 are mounted in such manner as to straddle the tube 32 when the plates 38 and 39 are closed, and registering openings 47 are provided in the opposite plate to receive the pointed ends of the pins therein.

The pins 46 may, if desired, be rigidly mounted in the plate, but I prefer to employ a simple means for removably securing the pins thereon for replacement when necessary. In the present instance, this means comprises a groove 48 formed in the outer side of one of the plates having at one side of the groove a pair of openings 49 through the plate to receive the needles 46. The opposite side of the groove is formed at an angle to the plate to provide a cam surface 50. A suitably shaped wedge 51 is arranged to fit within the groove with an angled surface thereon, adapted when the wedge is forced into the groove by any suitable means as the screws 52 to ride on the complementary surface of the groove and bind the outer ends of the pins 46 against the opposite surface of the groove.

In this manner a secondary needle sup-

porting means is provided which, as the tube 32 is retracted during the process of feeding the material upon the needle, will engage the material thereabout to prevent any bending or buckling of the needle.

The operation of the machine is exceedingly simple and efficient. The material is guided into the rolls 16 and 17 from the table 24 and is propelled therethrough by the operation of the hand ratchet 22. As the material is fluted by the toothed rolls each fold is pierced by the needles 20 and is pushed rearwardly thereon. As material accumulates upon the needles and bears upon the ends of the needle supporting tubes 32 the tubes will be forced rearwardly between the hinged plates 38 and 39, which, of course, are closed. When the tubes have been retracted to the free edge of the plates and the material has become packed upon the needle ends, it becomes necessary to part the plates and manually distribute the material rearwardly upon the needles as far as possible. Obviously, at this time, the tubes are retracted farther along the needles. When the plates are again closed and clamped some of the pins 46 straddle the needles and penetrate the material to provide the secondary supporting means. The fluting operation may now be continued until completed, the plates being parted and the material distributed along the needles as often as is necessary. After completion of the process the needles together with the material thereon are removed from the machine, the tubes 32 being then entirely retracted and the plates 38 and 39 being parted so as to permit such removal. The material may then be withdrawn onto threads in the usual manner.

It is apparent that I have provided a simple and very effective fluting machine, in which any possibility of the needles bending is positively and effectively prevented.

I claim as my invention:

1. A fluting machine having, in combination, a pair of toothed rolls adapted to form flutes in a piece of material, a needle positioned in relation to said rolls to receive said flutes thereon, primary needle-supporting means arranged to prevent bending of said needle at the start of the fluting operation comprising a member slidably longitudinally of the needle towards and from the point thereof and adapted when moved away from the point of the needle to expose an increased length of the needle and secondary needle-supporting means arranged to supplant the said primary means after a certain amount of material has been received on said needle, said secondary means normally surrounding and guiding said member.

2. A fluting machine having, in combination, a pair of toothed rolls adapted to form flutes in a piece of material, a needle arranged relative to said rolls for receiving

said flutes thereon, means to mount said needle including a support at the rear end of the needle and means for holding said needle straight, including a member slidably longitudinally of the needle towards and from the point thereof, said means being retractable to expose said needle as said material is received thereon.

3. A machine of the character described having, in combination, a pair of driven toothed rolls, a needle arranged to receive material from said rolls, and means arranged longitudinally of the needle to prevent bending thereof, said means comprising a support extending longitudinally of the needle and a plurality of pins thereon adapted to pierce the material on said needle at a plurality of points along the length thereof to provide a positive holding engagement between said means and said needle.

4. A fluting machine having, in combination, a pair of driven toothed rolls, a needle arranged relative thereto for receiving material from said rolls, a support for the rear end of the needle, and a pair of plates pivotally mounted on said support on opposite sides of said needle and arranged when said plates are parallel to extend forwardly from said support and to lie longitudinally along said needle and in a position closely adjacent said needle throughout the major portion of the length of the needle to prevent the needle from bending.

5. A fluting machine having, in combination, a pair of driven toothed rolls, a needle arranged relative thereto for receiving thereon material from said rolls, a support, and a pair of plates pivotally mounted on said support, one on each side of said needle, means securing said plates one to the other with said needle therebetween, and a plurality of pairs of coacting complementary parts on said plates positioned at spaced points longitudinally of the needle and arranged to grip the material on said needle adjacent the needle to prevent bending thereof when said plates are closed.

6. A fluting machine having, in combination, a pair of driven toothed rolls, a needle arranged relative thereto for receiving thereon material from said rolls, a support, and a pair of plates pivotally mounted on said support one on each side of said needle, means securing said plates one to the other with said needle therebetween, and a plurality of pointed pins on one plate arranged to straddle said needle at various points along the length thereof, which pins are adapted to engage the material on said needle to hold said needle against bending.

7. A fluting machine having, in combination, a pair of driven toothed rolls, a needle for receiving material therefrom, a pair of plates pivotally mounted adjacent to but on diametrically opposite sides of said needle,

- means for clamping one plate to the other with said needle therebetween, a tube slideable on said needle and between said plates and a plurality of pair of pins on one plate straddling said tube and said needle, said tube being removable to expose an increasing length of said needle as the material is received thereon, said pins being arranged to engage said material as said tube is retracted from said needle.
8. A fluting machine having, in combination, a pair of rolls adapted to form flutes in a piece of material, a needle arranged relatively to said rolls for receiving said flutes thereon, and a tubular member within which said needle is supported, said tubular member being slideable relatively thereto to permit an increasing amount of material to be received on said needle.
9. A fluting machine having, in combination, a pair of driven toothed rolls adapted to form flutes in a piece of material, a flute receiving needle positioned to penetrate the flutes issuing from said rolls, a rod abutting the rear end of said needle, and a tubular member slideable relatively to said needle and telescoping upon said needle and rod, said tubular member being arranged to prevent the bending of said needle as said needle receives the material and to hold said needle against displacement from its abutting relation with said rod.
10. The combination with a needle arranged to receive fluted material from a pair of driven fluting rolls, primary means arranged to support said needle against bending and movable as said material is received thereon to expose said needle for the reception of the material thereon, and secondary means arranged to supplant said primary means in supporting said needle as said needle becomes exposed by the movement of said primary means.
11. A fluting machine having, in combination, fluting rolls, a needle for receiving material therefrom, a pair of plates pivotally mounted adjacent to and on opposite sides of said needle, means for clamping said plates together with the needle therebetween, and a tube slideable on said needle and between said plates, said tube being movable to expose an increasing length of needle as the material is received thereon.
12. A fluting machine having, in combination, rolls adapted to form flutes in a piece of material, a needle arranged relatively to said rolls for receiving the fluted material thereon, a tubular member within which said needle is supported, said tubular member being slideable relatively to the needle to permit an increasing amount of material to be received on said needle, a support having a portion lying along the needle and a plurality of pins on said support straddling said tubular member at a plurality of places and adapted

to prevent the needle from bending when the tube is withdrawn.

In testimony whereof, I have hereunto affixed my signature.

SERAPHINE F. BAUWENS.
